UNITED STATES PATENT OFFICE

PIERRE H. MEYER, OF NEW YORK, N. Y.

DISPLAY APPARATUS

Application filed June 28, 1930. Serial No. 464,456.

This invention relates to display apparatus, and particularly to combination counter and shelving display, of such structure as to be more or less universal in its adaptation for the display of merchandise of various kinds and classes in the arrangement of the shelves with respect to each other and to the counter, and the shelving generally speaking, with respect to counter displays; and the object of the invention is to provide a simple and economical construction of shelving of the class specified, which may be readily set up in a store, sales room or in like places, and which will occupy the least amount of space, and utilize such space to the best possible advantage in displaying merchandise so as to be readily seen and accessible; a further object being to provide means for supporting display cards or boards at the ends and intersections of shelving of the class specified, whereby predetermined or featured merchandise may be set out from the remainder of the display and be more readily noticeable, and which by virtue of the mounting employed, may, as a unit, be detached from the shelving for examination; and with these and other objects, in view, the invention consists in an apparatus of the class and for the purpose specified, which is simple in construction, efficient in use, and which is constructed as hereinafter described and claimed.

The invention is fully disclosed in the following specification, of which the accompanying drawings form a part, in which the separate parts of my improvement are designated by suitable reference characters in each of the views, and in which:

Fig. 1 is a front view of a counter and shelving apparatus, made according to my invention.

Fig. 2 is a section on the line 2—2 of Fig. 1.

Fig. 3 is a partial section on the line 3—3 of Fig. 1.

Fig. 4 is a perspective detail view of one of a number of display boards, which I employ.

Fig. 5 is a partial section on the line 5—5 of Fig. 1.

Fig. 6 is a partial section on the line 6—6 of Fig. 2; and,

Fig. 7 is a sectional, detail view showing a modified arrangement of shelf boards in the shelving.

For the purpose of illustrating one method of carrying my invention into effect, I have shown in Figs. 1 and 2 of the drawings, a counter construction 10, consisting of a table member 11, a front flange wall 12, supporting legs 13 having transverse members 14 upon which shelves 15 may be arranged beneath the table 11.

At the back of the table 11 is arranged a vertically projecting backboard 16, in connection with which is supported a plurality of vertically arranged shelf standards 17, the lower outer corners of which are rounded as seen at 18, and the upper ends of which are jointed to another backboard 19, to which and the standard 17 is attached a top shelf member 20, having suitable mold and finishing strips 21, which join the upper ends of the standards 17 as will be apparent. Attached to opposite sides of the standards 17 at the rear edges thereof are strips 22 which limit the inward movement of the shelves 23 arranged thereon. The strips 22 do not extend the full height of the standards 17 and are arranged adjacent a plurality of transverse slots 24 formed on the opposite side faces of the standards. Placed in these slots are shelf supporting plates or cleats 25 in the form of metal strips which fit snugly in the slots 24 and project therebeyond to support the shelves 23. By employing a relatively large number of the slots 24, it will be apparent that any desired adjustment of the shelves with respect to each other may be provided and the supporting cleats form firm and rigid supports for the shelves. I also preferably mount on the front edge of the standards 17 or the upper ends thereof, upwardly projecting clips or lugs 26 forming hooks adapted to engage sockets 27 in display boards or finishing strips 28 to be arranged on the outer faces of said standards. The sockets 27 are reinforced by plates 29 attached to the rear face of said boards.

Secured to the inner face of the boards or strips 28, adjacent the lower ends thereof, are spaced L-shaped plates 30, which serve to

align the boards on the standards, these plates fitting on opposite side faces of the standards 17, as clearly illustrated in Fig. 5 of the drawings.

5 In Fig. 1 of the drawings, I have shown at the left of the shelving, a finishing strip 28 which is comparatively narrow, whereas the other two strips or boards 28 are employed for display purposes. That is to say, articles 10 of merchandise of various kinds and classes may be supported upon the outer faces of these boards to form displays arranged between the separate sections of the shelving disposed between the standards. By virtue of 15 the manner of attachment of the boards 28 employed, it will be apparent that the same may be quickly attached and detached whenever desired.

By providing a combination counter and 20 shelf construction of the class described, it will be apparent that articles of merchandise placed on the counter for display may be readily seen, even those articles arranged at the back of the counter or the table 11 thereof. 25 When relatively large articles are employed on the counter, the arrangement of the shelves 23 within the standards will be such as to suit such articles. For example, in the central section of the shelving shown in Fig. 1, the 30 lowermost shelf designated by the reference numeral 23a, is arranged at a relatively high distance from the table 11 as compared with the lowermost shelves in the two end sections, thus accommodating the central portion of 35 the counter to relatively tall articles.

In some instances, it would be desirable to support articles in angular position within and between the standards 17, especially on the lower shelves of the separate sections; 40 and for this purpose, I have shown a modification in Fig. 7 of the drawings, which consists in providing a shelf board 31, wider than the shelf boards 23 and including a front flange 32 arranged at an acute angle with respect to the upper face of the shelf board 31. 45 This board also includes angular side blocks 33 adapted to rest upon the supporting clips 25 so as to arrange the shelf in an angular position such as shown in said figure. It will 50 be understood that the rear side corners of the shelf 31 will be cut away to clear the strips 22.

It will also be apparent that any desired 55 number of shelf boards 23 may be arranged in the separate sections in a spaced relation suitable for the articles of merchandise placed on display therein. While I have shown in Fig. 1 of the drawings, an arrangement of three sections, it will be apparent that any 60 desired number of sections may be employed by adding the required number of spaced standards, and by correspondingly lengthening the counter, although it is not necessary 65 that the length of the shelving be equal to that of the length of the counter. Instead of ar-

ranging the shelving and counter adjacent a wall as indicated in Fig. 2 of the drawings, two of these counter constructions may be arranged back to back.

It will also be understood that whenever 70 desired, all of the shelf boards may be removed between opposed standards so as to permit the mounting of relatively tall articles upon the counter, or articles may be arranged upon the wall space between the 75 standards if desired. Various other changes in and modifications of the construction herein shown and described, may be made within the scope of the appended claims without departing from the spirit of my invention 80 or sacrificing its advantages.

Having fully described my invention, what I claim as new and desire to secure by Letters Patent, is:

1. In apparatus of the class described, a 85 plurality of spaced standards, means for supporting said standards in spaced relation, said standards comprising elongated boards of the same width throughout the major portion of the length thereof with their wide faces in opposed relation, the wide faces of said standards having a plurality of transverse grooves opening through the front and rear edges thereof and spaced vertically thereon in close proximity to each other, elongated 90 shelf supporting plates fitting snugly in said grooves and projecting beyond adjacent side faces of the standards to form shelf supporting cleats, a plurality of shelf boards adapted 95 to be supported upon said cleats to arrange the shelf boards in predetermined spaced relation vertically within said standards, finishing and display boards of greater width than the thickness of said standards detachably arranged on the outer edges thereof, 100 and means for detachably mounting said boards in connection with the standards.

2. An apparatus of the class described comprising a plurality of spaced standards, means for supporting said standards in spaced 110 relation, said standards comprising elongated boards of the same width throughout the major portion of the length thereof with their wide faces in opposed relation, the wide faces of said standards having a plurality of transverse grooves opening through the front and rear edges thereof and spaced vertically thereon in close proximity to each other, elongated 115 shelf supporting plates fitting snugly in said grooves and projecting beyond adjacent side faces of the standards to form shelf supporting cleats, a plurality of shelf boards adapted 120 to be supported upon said cleats to arrange the shelf boards in predetermined spaced relation vertically within said standards, and means on the shelf boards for supporting said boards on the cleats in angular position.

3. An apparatus of the class described comprising a plurality of spaced standards, means for supporting said standards in spaced rela- 125

tion, said standards comprising elongated boards of the same width throughout the major portion of the length thereof with their wide faces in opposed relation, the wide 5 faces of said standards having a plurality of transverse grooves opening through the front and rear edges thereof and spaced vertically thereon in close proximity to each other, elongated shelf supporting plates fitting snugly in 10 said grooves and projecting beyond adjacent side faces of the standards to form shelf supporting cleats, a plurality of shelf boards adapted to be supported upon said cleats to arrange the shelf boards in predetermined 15 spaced relation vertically within said standards, means on the shelf boards for supporting said boards on the cleats in angular position, finishing and display boards of greater width than the thickness of said standards 20 detachably arranged on the outer edges thereof, and means for detachably mounting said boards in connection with the standards.

4. An apparatus of the class described comprising a plurality of spaced standards, means 25 for supporting said standards in spaced relation, said standards comprising elongated boards of the same width through the major portion of the length thereof with their wide faces in opposed relation, the wide faces of 30 said standards having a plurality of transverse grooves opening through the front and rear edges thereof and spaced vertically thereon in close proximity to each other, elongated shelf supporting plates fitting snugly in said 35 grooves and projecting beyond adjacent side faces of the standards to form shelf supporting cleats, a plurality of shelf boards adapted to be supported upon said cleats to arrange the shelf boards in predetermined spaced relation 40 vertically within said standards, means on the shelf boards for supporting said boards on the cleats in angular position, and the front end of said shelf boards having upwardly projecting retaining flanges.

45 In testimony that I claim the foregoing as my invention I have signed my name this 23rd day of June, 1930.

PIERRE H. MEYER.
